UNITED STATES PATENT OFFICE.

ARTHUR GARFIELD TRIMBLE, OF PITTSBURGH, PENNSYLVANIA.

ORNAMENTAL PIN OR BADGE.

1,270,347.

Specification of Letters Patent. Patented June 25, 1918.

Application filed March 26, 1918. Serial No. 224,790.

To all whom it may concern:

Be it known that I, ARTHUR GARFIELD TRIMBLE, a citizen of the United States of America, residing at Pittsburgh, in the

5 county of Allegheny and State of Pennsylvania, have invented certain new and useful Improvements in Ornamental Pins or Badges, of which the following is a specification.

10 This invention relates to an ornamental pin or badge employed as a reward or merit emblem, and is designed primarily for use where it is desired to recognize faithfulness of attendance or service of scholars or teachers at Sunday schools, educational institutions and also of employees in various commercial pursuits, or in any other connection wherein its use will be found applicable, and has for its object to provide, in a manner 15 thereafter set forth, a merit or reward emblem which will eliminate the necessity of giving several independent emblems, to be attached together, as a further or additional reward or merit to the person entitled to the 20 same.

Further objects of the invention are to provide an ornamental pin or badge constituting a merit emblem which is simple in its construction and arrangement, strong, 25 durable, efficient in its use, conveniently set up, by its employment materially decreasing cost of use over the present type of merit emblems now employed, and comparatively inexpensive to manufacture.

30 With the foregoing and other objects in view this invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which come within the scope of the claims hereunto appended.

40 In the drawings wherein like reference characters denote corresponding parts throughout the several views:

Figure 1 is a perspective view of an ornamental pin or badge in accordance with this 45 invention.

Fig. 2 is a front elevation.

Fig. 3 is a section on line III—III Fig. 2.

Fig. 4 is a vertical section on line IV—IV Fig. 6 of the bezel.

50 Fig. 5 is a vertical sectional view of the pin or badge with the bezel attached.

Fig. 6 is a face view of the bezel.

Fig. 7 is a rear elevation of the pin or badge illustrating the arrangement for fastening the bezel.

Fig. 8 is a front elevation of the pin or badge with the bezel attached.

Briefly described the invention comprises a body portion in the form of an annulus having suspended therein a pendant, the latter indicating a certain period of attendance, service, position or class. By way of example, days, weeks, months or years when indicating attendance or service, first place, second place, etc., when indicating position in contests and first class, second class, etc., when indicating class. The pendant is detachable, so that it can be removed and pendant indicating greater merit or reward substituted therefor. By this arrangement it overcomes the employment in the merit emblem of bars or other devices which are successively connected together and arranged exteriorly of the body portion making the pin or badge eventually of great length and somewhat objectionable to wear.

Referring to Figs. 1, 2 and 3 of the drawings 1 denotes a flat annulus having its inner edge formed with an eye 2, to which is detachably connected the merit or reward pendant 3. As illustrated the pendant is shown by way of example to indicate "10" provided with a transverse panel 4, having an inscription to indicate years as at 5. Means are provided as at 6, for detachably connecting the body portion 1 to the garment of a person.

The inscription 5, indicating years, may be changed to days, weeks or months, or first place, second place, etc., or first class, second class, etc.

The annulus may be suitably colored to indicate a certain division or a class or provided with an inscription as at 7, to indicate the name of the Sunday or day school, employer, college, order, society, etc., to which the pin or badge belongs or is issued by.

The pendants 3, which are to be suspended within the body portion 1, can run consecutively from one to one thousand, and which is provided with a panel 4 for the purpose heretofore referred to.

Associated with the body portion 1, as shown in Figs. 4 to 8, is an ornamental bezel 8, secured in position by the hold-fast devices 9. This bezel 8, may be constructed of plain gold, gold engraved, enameled

or set with jewels or stones, and said bezel 8, designates class and additional rewards when used by Sunday schools in particular, which is to indicate each five year period up to twenty-five years or more.

The use of the bezel however, is optional, as the badge consisting of the body portion and pendant can be considered complete.

What I claim is:

- 10 1. A badge comprising a body portion in the form of an annulus having its inner edge provided with an eye and a pendant connected to said eye and surrounded by the body portion and consisting of a numerical designation and provided with a transverse panel having a conventional inscription associated with said designation.
- 15 2. A badge comprising a body portion in the form of an annulus having its inner edge provided with an eye and a pendant connected to said eye and surrounded by the body portion consisting of a numerical designation and provided with a transverse panel having a conventional inscription as-
- 20 20

Copies of this patent may be obtained for five cents each, by addressing the "Commissioner of Patents, Washington, D. C."

sociated with said designation, and a bezel 25 inclosing the annulus and secured thereto.

3. A badge comprising a body portion, a pendant suspended within the body portion and consisting of a numerical designation provided with a transverse panel 30 having a conventional inscription associated with said designation.

4. A badge comprising a body portion and a pendant suspended therein and having conventional means to designate the degree of merit of the badge.

5. A body comprising a body portion having conventional means to indicate the source of issuance thereof, and a merit indicating means suspended within said body 40 portion.

In testimony whereof I affix my signature in the presence of two witnesses.

ARTHUR GARFIELD TRIMBLE.
